UNITED STATES PATENT OFFICE.

MAX LITTMANN, OF ST. LOUIS, MISSOURI.

LINE-RING FOR HAMES.

SPECIFICATION forming part of Letters Patent No. 416,633, dated December 3, 1889.

Application filed July 16, 1889. Serial No. 317,714. (No model.)

To all whom it may concern:

Be it known that I, MAX LITTMANN, of the city of St. Louis, in the State of Missouri, have invented a certain new and useful Improvement in Line-Rings for Hames, of which the following is a full, clear, and exact description, reference being had to the accompanying drawings, forming part of this specification.

10 This invention relates to a swiveled line-ring whose bearings outside the ring exercise a dominant favorable influence on the action of the ring, in contradistinction to a bearing or bearings within the ring, in which the action of said ring exercises adverse leverage on said bearings; and the invention consists in features of novelty hereinafter fully described, and pointed out in the claim.

Figure I is an edge view of a hame with 20 my elongated swivel-bearing line-ring attached thereto, and Fig. II is a side view of the same.

Referring to the drawings, 1 represents the hame, and 2 the line-ring, the inner part of 25 which line-ring forms an integral part of the swivel-bar 3, whose extension journal-pins 4 reach beyond the ring both above and beneath and work within the journal bearings or eyes 5 of the staples 6, which are swaged 30 around the journal-pins. The two journal bearings or eyes of said staples engage the journal-pins 4 respectively above and below the ring between the projecting knobs 7 on the ends of said journal-pins, which form 35 guide-beads of larger diameter than the journal-pins outside said staples and enlarged shoulders 8 between said journal-bearings and the line-ring, which form guide-beads of larger diameter than the journal-pins inside 40 said staples. The two limbs of the staples are passed through perforations 9 in the metal strap 10 and through the hame, on the inside of which hame the points of said staples are passed through the washers 11, to 45 which they are secured by their riveted ends 12, so as to firmly hold the swivel journal-bearing of the line-ring in its attachment to the hames.

13 represents the tug-attachment staple,

which passes through perforations 14 in the 50 shield-bracket 15 and through the hame, and is secured by its riveted ends 16, that are clinched on the washers 17 on the inside of said hame; and 18 is the breast-strap ring, which works within the eyelet 19 in the lug 55 20, that projects from said bracket.

Now it will be seen that the line-ring has a swivel-bar journal-bearing attachment beyond the ring itself both above and below. This provides a far more steady and reliable 60 journal-bearing on which the line-ring swivels than could be effected either with the usual single journal-bearing of an eyelet-bolt with a single central attachment or of a double bearing within the line-ring and from 65 the inner side of said ring. It will be seen that even in the latter case the action of the lines on the ring exerts a more or less adverse leverage on the bearings, so that they work with less regularity and ease and are more 70 apt in time to get twisted and wrung off from their attachment. It will also be seen that after the bearing attachments get twisted from the true the adverse leverage exerted on them increases in its adversity. As the 75 swivel-bar and its journal-bearing in this device is thus placed outside or beyond the line-ring, it holds and governs by its favorable leverage, instead of being held and governed by the adverse leverage exerted by said 80 ring under the constantly-changing movements of the lines in said ring. Also, by the increased distance apart of the perforations through the hame for seating the staple than that used where either a single or double eye-bolt or staple secures the attachment within the ring, the hame is itself much stronger and less liable to break where perforated, as 85 said cut-aways are too far removed from each other to run much risk of the hame 90 splitting on a line from one to the other, as it sometimes does when under a heavy draft, when the staple-holes are necessarily near together, when the attachment is from points within the ring. The said tendency to break 95 when under a heavy draft-strain across the line of adjacent holes is also decreased by the aforesaid-stated fact that there is in my de-

vice no adverse leverage being exerted on the journal-bearings whose attachments are seated within said perforations.

I claim as my invention—

- 5 The combination, with a hame, of a line-ring provided with two journals extending outside of said ring on the side adjacent to said hame, and two staples having eyes and

shanks formed integral, the said eyes forming bearings for the journals, substantially as described.

MAX LITTMANN.
